S. A. CRONE

RAILWAY BRAKE BEAM

Filed May 12, 1922

Fig. 5

Seth A. Crone INVENTOR

BY

Chas. C. Bell

ATTORNEY

UNITED STATES PATENT OFFICE.

SETH A. CRONE, OF EAST ORANGE, NEW JERSEY.

RAILWAY BRAKE BEAM.

Application filed May 12, 1922. Serial No. 560,339.

To all whom it may concern:

Be it known that I, SETH A. CRONE, a citizen of the United States, and a resident of East Orange, in the county of Essex and State of New Jersey, have invented certain new and useful Improvements in Railway Brake Beams, of which the following is a specification.

The invention pertains more particularly to trussed-beams for railway cars and especially to a novel support at the forward end of the strut to receive a sliding chair for a third point suspension or a link suspension.

I have illustrated my invention herein as applied to a reversible strut of the character specifically described in my pending application for Letters Patent, Serial No. 532,465, filed January 28, 1922, which has now become Patent Number 1,432,234 dated October 17, 1922, and also to a non-reversible one-piece forged metal strut, the novel feature of my invention being applicable to the forward end of either a reversible strut or a non-reversible strut. The strut in either case presents a solid forward end connecting the two-side members of the strut, and to this end I apply the novel supporting attachment constituting my invention, this attachment being of forged metal and formed from an integral or one-piece blank and having a rear end to be secured to the forward end of the strut and two apertured side arms affording seats for the tension member or truss rod and means for supporting a sliding chair for a three-point suspension or properly receiving the lower end of a link suspension.

The present invention pertains therefore to a special supporting bracket to be secured to and for use in combination with the forward end of the strut of a trussed brake-beam, said bracket having two arms and therefore being of duplex character and said arms affording seats for the central portion of the truss-rod and means for receiving a sliding chair suspension or the lower end of a link suspension.

The invention will be fully understood from the detailed description hereinafter presented, reference being had to the accompanying drawings, in which:

Fig. 1 is a top view of a portion of a

brake-beam having a compression member, a tension member and a strut equipped with the supporting bracket of my invention, the strut in the construction shown being reversible and illustrated with its corresponding sides turned vertically;

Fig. 2 is a side elevation of the same, the compression and tension members of the brake-beam being shown in section;

Fig. 3 is a top view of a non-reversible strut equipped with my invention, the compression and tension members of the beam being shown in section;

Fig. 4 is an upper edge view of the forged metal blank from which the supporting bracket of my invention is formed, and

Fig. 5 is a face view of the same, Figs. 4 and 5 showing the blank in its flat condition and prior to being shaped into the form illustrated in Figs. 1, 2 and 3.

In the drawings, 10 designates a channel shaped compression member of a brake-beam, 12 the truss rod, and 9 a reversible strut having corresponding side members 13 and a flat end member 14 connecting said sides. The strut shown in Fig. 1 is of the reversible type described in detail in my aforesaid application No. 532,465, and I do not deem it necessary to describe the features connecting the back end of the strut with the compression member in a manner rendering the strut reversible, since there are many forms of reversible struts and the form illustrated in Figs. 1 and 2 may be regarded merely as illustrative of one form of reversible strut. The compression member 10 is shown as of channel shape, but in respect to my invention said compression member may be of any suitable or desirable shape adapted to receive the strut. The truss rod 12 is of the usual type and affords a tension member.

Upon the forward end 14 of the strut 9 is swiveled the supporting bracket 15 of my invention, this bracket comprising, in one integral piece, two forwardly projecting parallel side arms 16 and a back end member 17 connecting said arms and adapted to be secured against the forward flat end 14 of the strut 9. The support or bracket 15 is formed from a blank of forged or wrought metal and is primarily in the flat as shown

in Figs. 4 and 5. The side arms 16 of the support or bracket 15 correspond with each other and are arched downwardly and forwardly and at their forward ends are formed with transverse openings 18 encircled by bushings 19, serving to strengthen the arms at the openings 18 therein and to afford broad bearings for a bolt or other means by which a chair, not shown, for a third point suspension, may be applied to said support or bracket.

The blank shown in Figs. 4 and 5 is bent to form the back end 17 and forwardly projecting sides 16, and said end 17 is apertured, as at 20, to receive a pin or rivet 21, by means of which the support or bracket 15 is connected with the end 14 of the strut 9, said end 14 being also apertured to receive said pin or rivet 21, as indicated by dotted lines in Figs. 1 and 2. The pin or rivet 21 has a counter-sunk head at the forward face of the end 17 of the support or bracket and may have an exposed head 22 on its opposite end. In the construction shown in Figs. 1 and 2 the pin or rivet 21 is loosely headed at its rear end and forms a swivel around which the strut 9 may be turned to the right or left for positioning the same. In their lower sides back of the openings 18, the side members 16 of the support or bracket 15 are recessed, as at 23, to form seats for the truss-rod or tension member 12, the recesses 23 curving backwardly and then forwardly and having at their lower sides forwardly projecting extensions 24 which extend below a portion of the truss-rod and aid in setting said rod in longitudinal line with the strut. The recesses 23 have forward edges which curve upwardly and backwardly, as shown in Fig. 2, and serve to direct the truss-rod to the back portion of said recesses and above the extensions 24. The central vertical portion of the blank shown in Figs. 4 and 5 forms the back end 17 of the support or bracket 15 and thence the corresponding side portions of said blank are bent forwardly to create the parallel arms 16 having the recesses 23 and extensions 24, the whole being in one integral forged or wrought metal plate.

In Fig. 3 I illustrate the same support or bracket 15 applied to the flat forward end 25 of a non-reversible strut 26, this strut 26 being formed from a bar of forged metal and the details of which need not be herein described. The support or bracket 15 of Fig. 3 is secured by a rivet 27 to the end 25 of the strut 26, and since the strut 26 is not reversible, the rivet 27 may rigidly secure the support or bracket 15 in fixed relation to the strut 26.

I do not limit my invention to the special construction of the strut, since the same is applicable to any strut having a forward end adapted to receive it. My invention com-

prehends the particular construction shown of the support or bracket 15 formed of a single stamping of forged metal, in combination with the strut, whether reversible or not, and adapted to receive the tension member 12 and also afford means for receiving the chair, not shown, of a third point suspension or a link suspension, not shown, both forms of suspensions being familiar in this art.

What I claim as my invention and desire to secure by Letters-Patent, is:

1. A brake-beam comprising a compression member, a tension member, a strut extending between said members and having a forward flat end portion and parallel sides and a support or bracket for a third point suspension having a back and forwardly projecting parallel arms and secured at said back against the flat forward end of said strut, said support or bracket being in one integral stamping of forged metal and said arms having apertures formed therein, with bushings around the same, to receive the securing means for the suspension member and being recessed in their lower sides back of said apertures to receive and afford seats for the central portion of the tension member.

2. A brake-beam comprising a compression member, a tension member, a strut extending between said members and having an apertured forward end portion and parallel sides and a support or bracket for a third point suspension having an apertured back plate member and forwardly projecting parallel arms and secured at said back to the forward end of said strut, the securing means being a headed pin applied through said apertures in said back member and the forward end of the strut, said support or bracket being in one integral stamping of forged metal and said arms having apertures formed therein for the securing means for the suspension member and being recessed upwardly and backwardly in their lower sides to receive and afford seats for the tension member, said recesses being partly closed below the tension member by extensions projecting forwardly from the lower back portion of the support or bracket and below said tension member.

3. A brake-beam comprising a compression member, a tension member, a reversible strut extending between said members and having an apertured forward end portion, a support or bracket for a third point suspension having an apertured back plate member engaging said forward end of the strut and forwardly projecting parallel side arms, and a pin inserted through said back and said forward end of the strut and swiveling the support or bracket to the strut, said support or bracket being in one integral stamping of forged metal and said arms

having apertures formed therein for the securing means for the suspension member and being recessed upwardly and backwardly in their lower sides to receive and afford seats for the tension member, said recesses being partly closed below the tension member by extensions projecting forwardly

from the lower back portion of the support or bracket and below said tension member.

Signed at New York city, in the county ¹⁰ of New York and State of New York, this 10th day of May, A. D. 1922.

SETH A. CRONE.
